UNITED STATES PATENT OFFICE

WILLIAM EDWARD PRESCOTT, OF LONDON, ENGLAND, ASSIGNOR TO BAKER PERKINS COMPANY, INC., OF SAGINAW, MICHIGAN, A CORPORATION OF NEW YORK

MACHINE FOR BAKING WAFERS AND THE LIKE

Application filed June 4, 1925, Serial No 34,853, and in Great Britain June 27, 1924.

This invention relates to machines for baking wafers and the like, more particularly of that class in which the wafer material, such as batter in a more or less liquid condition, is fed on to the surface of moulds or plates which are then closed by hinged covers, the moulds being passed continuously, for example in endless fashion, through a baking chamber or otherwise heated, after which the covers are opened and the baked wafers removed.

The present invention embodies improved means for feeding the wafer material to the moulds or plates, such means including a pump which delivers a measured or definite quantity of the batter to a nozzle or nozzles which in turn deposit it on each mould as it passes a definite position in the machine.

According to this invention the nozzle or nozzles is or are so constructed and actuated as to receive a compound movement, that is to say, a rectilinear or curvilinear movement for depositing the batter in what ever direction in relation to the mould edges it is to be laid, and a second arcuate or swinging movement at generally right angles to the first movement to place the nozzle over the mould and remove it therefrom, these latter movements taking place whilst the mould cover is opening and closing again.

The nozzle or nozzles is or are also so constructed and arranged as to deposit thin paths or lines of batter on to the mould in comparatively close formation and either in a direction parallel to the edges thereof, or in a direction at a right or other angle to said edges or in curved lines in relation thereto.

The invention also comprises other features of construction and arrangement and combinations of parts as set forth in appended claims and hereinafter described with reference to the accompanying drawings in which:

Fig. 1 is a plan view showing a nozzle and its associated operating mechanism for delivering rectilinear lines of batter to a mould, Fig. 2 is a front elevation of Fig. 1 with parts removed for clearness of illustration: Fig. 3 is an extended sectional view of the batter pipe taken in a single plane for showing its connections to the nozzle and

parts of the operating mechanism; Fig. 4 is a plan view showing a modification in which nozzles are adapted to deposit curved lines of batter on a mould and Fig. 5 is a front or edge view of parts illustrated in Fig. 4.

To firstly refer to Figs. 1 to 3, the mechanism here illustrated is shown as applied to parts of a known wafer biscuit baking machine the reference *a* designating a portion of a side frame thereof on which the mechanism is mounted, the moulds *b* being carried through the machine by means of links *b*¹ having rollers *b*² travelling on guides *b*³ on the inside of the frame. From the latter extend upwards rods *b*⁴ and *b*⁵ which guide the covers of the moulds to open and close them as they travel through the machine. In Figs. 1 and 3 *c* designates the main batter supply pipe which is oscillated about its axis by suitable means, usually rack and pinion mechanism, from a moving part of the machine within the limits denoted by the broken lines *x*, *x*¹. Excess of batter is delivered through extension *c*¹ of the pipe *c* back to a convenient receptacle.

The above mentioned parts are common to the type of machine mentioned, and to now turn to the features of the present invention, the nozzle *d* having a series of spaced outlets *d*¹ for producing the deposit of lines of batter on the mould *b*, is carried at the free end of a pipe *d*² the other end of which is rigidly mounted in one side of a casting *d*³ which is adapted to slide in a rectilinear path on a bar *e* extending longitudinally of the machine parallel to the lateral edges of the mould.

The said casting is adapted to have some turning movement in relation to a pipe *e*¹ (Fig. 3) fitted to said casting by means of a gland *e*² and forming a continuation of the pipe *d*², said pipe *e*¹ extending angularly towards the side of the machine where it forms another casting *e*³ containing a gland *e*⁴ over which fits the enlarged end of a pipe *f* branching from the main batter pipe *c* and provided with a cock *f*¹ working over a graduated plate *f*² to control the supply of batter.

The casting *d*³ and guide bar *e* are mounted on a vertical sleeve *g*, mounted in a bracket

g^1 extending from the frame a of the machine, and adapted to oscillate about its axis g^4 , being for this purpose mounted on a bolt g^2 depending from said bracket and held therein by a nut g^3 . The casting d^3 also carries on its upper surface an anti-friction roller d^5 which bears against a cam-plate h connected at one end to a bracket h^1 and at the other end to the bracket g^1 by a resilient adjustable connection comprising a bolt h^2 and spring h^3 . The cam-plate is provided with a straight path h^4 followed by a curved path h^5 struck from a centre coinciding with the axis of oscillation g^4 of the casting d^3 and guide bar e .

15 With the parts as above constructed and arranged the operation will be as follows starting from the position shown in Fig. 1.

On the batter supply pipe c being oscillated to the left towards position x , the casting d^3 , pipe d^2 and nozzle d^1 will be removed forward over the mould b , being guided by the bar e and will reach the broken line position shown at y . The batter pipe c is then reversed to the mid-position during which time the nozzle 25 will discharge parallel rows of batter on to the mould until it reaches the full line position. The supply and cut off of the batter may be controlled by the oscillation of the pipe or by the suction and delivery of the pump or by 30 other appropriate means. Continued oscillation of the pipe c towards the position x^1 will cause the casting d^3 and guide bar e , with parts carried thereby, to be rocked bodily with an arcuate movement about the afore- 35 said axis g^4 during which time the roller d^5 on casting d^3 will follow the curved cam path h^5 . When the batter pipe c has been swung to the position x^1 the nozzle will have reached the position shown in broken lines at y^1 allowing the cover of the mould to close down 40 thereon for the baking operation. The movements described are permitted by the gland joints previously described in the batter pipes without affecting the passage 45 through same or permitting leakage.

To now refer to the modification shown in Figs. 4 and 5, the same operating mechanism from the main batter pipe c may be employed to produce the rectilinear movement of the 50 casting d^3 and the arcuate movements of same in conjunction with the guide bar e about the axis g^4 .

In this modification however the depositing movement of the nozzle is not a rectilinear 55 one but comprises movements in curved paths indicated by lines z in Fig. 4 extending from near an edge or corner at one end or side of the mold b inwards towards the centre and then outwards again to a similar position adjacent the edge or corner at the other end or side, such movements taking place in relation 60 to both sides of the mould and therefore requiring separate nozzles d^{10} to deposit the batter in thin lines following the paths indicated.

The deposit of the batter in the fashion stated has the advantage of causing it to spread more equally over the entire mould when the cover closes down thereon; it having been found in practice that with the straight line deposit as in the embodiment 70 first described, the batter had a tendency to ooze from the edges of the mould more freely at the centre of the length or width as the case may be than at other parts. With the lines of deposit curving away from such central part, as in the present modification, this tendency is obviated and the batter is caused to flow evenly right into the corners of the mould,

The nozzles d^{10} are mounted at the end of a batter delivery pipe j fitted into the casting d^3 which receives both the rectilinear movement and arcuate movement as before mentioned. At its free end the pipe j carries two spigots j^1 about the axis of each of which may turn another pipe j^2 carrying at its outer end a nozzle d^{10} in the form of a T head. Thus there are two such nozzles in alignment adapted to carry the batter over the mould or plate b and the required similar curvilinear movements are imparted to each by means of a relatively stationary cam-member which may be in the form of a plate k having two slots k^1 formed therein of converse curvature 85 to the lines of batter to be deposited, said slots being engaged by rollers or other anti-friction means l extending from extensions j^3 of the nozzle-supporting pipes j^2 so that as the aforesaid casting d^3 is given its rectilinear 90 movement on the guide bar e the nozzles will receive the required curvilinear movement, this being permitted by the pipes j^2 being capable of turning about the axes of the spigots j^1 . The cam plate k is shown as mounted on an arm k^2 carried by an extension g^5 of the sleeve g so that it may oscillate about the axis 95 g^4 as previously explained.

It will be obvious that in both forms shown and described the design of the nozzle operating and guiding means is such as to properly time the operations of the nozzle in relation to the speed of the moulds and the open and closed periods of their covers.

Any other appropriate nozzle operating 115 and batter feeding means may however be employed so long as the depositing in thin paths or lines is effected and the compound movements described are obtained, these movements being in contra-distinction to 120 merely parallel inward and outward or simple arcuate movements of the nozzle as in known prior constructions.

The invention is not limited to the exact construction, arrangement and combination 125 of parts hereinbefore described since the same may be varied within limits prescribed by the following claims without departing from the spirit of the invention.

What I claim as my invention and desire 130

to secure by Letters Patent of the United States is:—

1. A feed nozzle for liquid wafer material having means for producing two separate movements in relation to an associated mould viz, a depositing movement longitudinally of the mould and an arcuate movement to and away from the mould and means for imparting a curvilinear movement to the nozzle during longitudinal movement.
2. A nozzle for liquid wafer material having means for producing two separate movements in relation to an associated mould, viz, a substantially rectilinear sliding movement longitudinally of the mould for depositing material thereon and a non-depositing arcuate movement to and away from said mould and a jointed pipe carrying said nozzle and serving as a supply of wafer material thereto, said pipe taking part in the longitudinal and arcuate movements of the nozzles.
3. A nozzle for wafer and like baking machines carried by a jointed pipe serving for supply of wafer material to said nozzle, a slidable member carrying said pipe, a guide on which sliding member moves, and means for sliding said member on the guide whereby the nozzle is given a movement longitudinally of an associated mould, and means for oscillating said sliding member and guide about a common axis whereby the nozzle is given an arcuate movement to and away from the mould.
4. A nozzle for wafer and like baking machines carried by a hollow jointed element serving as a supply for wafer material to the nozzle means for imparting to said element both a rectilinear movement longitudinally of an associated mould and an arcuate movement to and away from said mould and means for converting the rectilinear movement of said jointed element into a curvilinear movement of the nozzle.
5. A nozzle for wafer and like baking machines having means for producing two separate movements of said nozzle in relation to an associated mould, viz, sliding means for effecting a curvilinear depositing movement longitudinally of the mould and of an amplitude substantially corresponding to the length thereof for depositing the material on the mould in curved paths, and pivotal means for effecting an arcuate non-depositing movement of the nozzle into and out of the path of the mould.

In witness whereof I have signed this specification.

WILLIAM EDWARD PRESCOTT.
